Co-Inventor James Lo and his company, Lomak, executed an assignment of the present patent family to one of the present assignee's parent companies (Unilever NV). The assignment was dated Dec. 5, 2016 and was initially copied and communicated by e-mail to Unilever on Dec. 9, 2016. In a document dated Dec. 28, 2016, Lomak purported to indicate that the signed documents shall be effective in conjunction with: (1) the coming Assignment in relation to an IP Assignment in respect of sharingof IP (2) the Central Commercial Terms contract; and (3) Third Party Manufacturing—Unilever's Purchasing Agreement that shall be signed. In an e-mail dated Aug. 2, 2017, Lomak's indicated that a Unilever representative had agreed to handle "all matters in relation to IP, no matter assignment or any other registrations, if any, during the formal execution of both CTC and UPA."
